UNITED STATES PATENT OFFICE.

OSCAR OWENS, OF SAN FRANCISCO, CALIFORNIA, ASSIGNOR TO THE AMERICAN TYPE FOUNDER'S COMPANY, OF NEW JERSEY.

CARBURETER.

SPECIFICATION forming part of Letters Patent No. 615,572, dated December 6, 1898.

Application filed November 12, 1897. Serial No. 658,321. (No model.)

To all whom it may concern:

Be it known that I, OSCAR OWENS, a citizen of the United States, residing at San Francisco, in the county of San Francisco and State 5 of California, have invented certain new and useful Improvements in Carbureters; and I do hereby declare that the following is a full, clear, and exact description thereof.

My invention relates to generators of explosive mixtures for operating gas or vapor engines, and particularly to that kind of a generator which is arranged as an attachment to such an engine and in which oil, such as crude petroleum, is vaporized by heat derived 10 from the exhaust mixed with air and supplied to the engine-cylinder in charges, which are successively exploded and exhausted after explosion.

My invention consists in improvements in 20 the construction and arrangement of a generator for this purpose and is fully described in this specification and shown in the accompanying drawings, in which—

Figure 1 is a side elevation partly broken 25 away to show a longitudinal section of the generator. Fig. 2 is a plan view with the outer shell broken away. Fig. 3 is a cross-section on line $x-x$ of Fig. 2.

A represents the generator, which is preferably a tubular casting adapted to be secured 30 in any suitable way to the exhaust-passage of the engine, so that the exhaust or product of each explosion shall pass through the central passage a and escape through the connected pipe b . The tubular part A is of substantially rectangular shape in cross-section, Fig. 3, and its upper surface is channeled, as shown at c , and provided with ribs d of less width than the channel and arranged alternately so as to make a tortuous passage from 35 end to end, Fig. 2.

The device is arranged on a slight incline from the horizontal, as shown. Below the central passage is a second passage e , communicating with the upper surface by one or more hollow legs f , and having a draw-off cock g . The main casting is surrounded by a shell A' to prevent the escape of heat and gas. Into this shell opens an air-pipe C, 50 which supplies air necessary to produce the

proper explosive vapor and an oil-supply pipe D, having regulating means and which drops the oil upon the channeled face of the casting at its elevated end. This oil spreads into a film or sheet and the incline of the surface 55 upon which it is deposited causes it to pursue a tortuous course toward the exhaust-inlet. The exploded charges from the engine entering and passing through the tube a at a high temperature correspondingly heat the surface 60 upon which the oil is traveling and vaporize the latter. The vapor mingles with and carburets the air, producing the explosive mixture which is drawn off at the gas-pipe E in condition to be used in the engine-cylinder. 65 The pipe E is supposed to be connected to the inlet of the engine, so that the suction stroke of the piston draws the explosive charge into the engine-cylinder, and also draws fresh air into the generator.

The residuum of the oil flows through the passages f and can be drawn off by the cock g .

F represents a vent-pipe located at the exhaust-inlet to the generator, and h is a valve in such vent by which it may be closed or 75 opened. A valve i is also placed in the exit-pipe b . This vent and valve can be used to prevent overheating of the generator. By opening the vent F and closing the pipe b the hottest portion of the exhaust escapes through 80 the vent, and I have found in practice that by this means the temperature of the generator is reduced and need never become excessive.

The construction by which I obtain a generating-surface heated by hot products of combustion in an interior tube gives a large extent of generating-surface and exposes all parts of it to the heating agent. This comparatively thin heating-plate produces very 85 quick and effective vaporization.

I have mentioned my apparatus as particularly designed for vaporizing petroleum; but it is capable of use in connection with coal-oil, gasolene, or with any oil adapted 95 to form an explosive mixture when mingled with air.

From the above description the operation of the device will be clearly apparent, but may be briefly stated as follows: The exhaust- 100

2
gases from the engine passing through the central passage *a* heat the walls of this passage to a high degree. The oil is admitted by pipe D and dropping upon the channeled 5 surface of the pipe A spreads in a thin film over said surface and is rapidly vaporized by the heat and mingles with and carburets the air which is admitted through the pipe C, thus producing the explosive mixture, which 10 is drawn out through the pipe E to the engine.

Having described my invention, what I claim is—

1. A carbureter comprising a casting having a channeled exterior heating-surface, and 15 adapted to be connected to the exhaust-passage of the engine, a passage through said casting for the exhaust, a second passage adjacent thereto and communicating with the heating-surface in order to receive the residuum left by vaporization, an inclosing shell, and air and oil pipes entering said shell, substantially as described.
2. In a carbureter, and in combination, an 25 inclosing shell having air and oil inlets, a heater within the shell having a channeled heating-surface, a flue through the heater adapted to be connected to the exhaust of an engine, a passage adjacent to said flue, tubes connecting said passage with the heating-surface, and a discharge-opening from said passage; 30 whereby the oil is vaporized and car-

bureted on the heating-surface by the exhaust passing through said flue, while the residuum passes through said tubes to said passage, and is discharged therefrom.

35

3. As an article of manufacture, a casting to form part of a carbureter, having a channeled surface, a flue extending through said casting below said channeled surface, a passage in the casting parallel to said flue, tubes 40 passing across the flue and connecting said passage and the channeled surface, and a discharge-opening from said passage.

4. In a generator for gas-engines and in combination, an inclosing shell having air 45 and oil pipes entering it, a generator within the same, and having a heating-passage and a heating-surface, said generator being adapted for connection with the exhaust-passage of the engine, an exhaust-vent between the 50 exhaust connection and said heating-passage and provided with a cut-off, and a cut-off for closing the said heating-passage, substantially as described.

In testimony whereof I have affixed my signature, in presence of two witnesses, this 4th day of August, 1897.

OSCAR OWENS.
